UNITED STATES PATENT OFFICE.

EDWIN B. HOWITT, OF NEW BRUNSWICK, NEW JERSEY.

DESIGN FOR A COLLAR-BUTTON.

SPECIFICATION forming part of Design No. 32,247, dated February 20, 1900.

Application filed December 1, 1899. Serial No. 738,924. Term of patent 14 years.

To all whom it may concern:

Be it known that I, EDWIN B. HOWITT, a citizen of the United States, residing at New Brunswick, in the county of Middlesex and State of New Jersey, have invented and produced a new and original Design for a Collar-Button; and I do hereby declare the following to be a full, clear, and exact description of the same, reference being had to the accompanying drawing, forming a part thereof.

Referring to the accompanying drawing, the figure represents a perspective view of a collar-button embodying my design drawn to an enlarged scale.

My design consists of a flat base A, substantially of egg-oval shape, a flat stem C, extending perpendicularly thereto, connected

to said base adjacent to the wider end of the base and being substantially the same width of the base at its connection therewith and narrowed at its upper end, and a flat loop B, joined to the narrowed part of the stem at one end of the loop and extending therefrom beyond the edge of the base.

What I claim, and desire to secure by Letters Patent, is—

The design for a collar-button herein shown and described.

In testimony whereof I affix my signature in presence of two witnesses.

EDWIN B. HOWITT.

Witnesses:

J. H. WERNER,
LYLE VAN NUIS.
